UNITED STATES PATENT OFFICE.

JOSEPH J. COSGROVE, OF RUTHERFORD, NEW JERSEY, ASSIGNOR TO COSGROVE COSGROVE CO., OF NEW YORK, N. Y., A PARTNERSHIP OF NEW YORK.

WATER-CLOSET CONNECTION.

1,407,734.

Specification of Letters Patent. Patented Feb. 28, 1922.

Application filed September 2, 1920. Serial No. 407,657.

To all whom it may concern:

Be it known that I, JOSEPH J. COSGROVE, a citizen of the United States, residing at Rutherford, in the county of Bergen and State of New Jersey, have invented certain new and useful Improvements in Water-Closet Connections, of which the following is a specification, reference being had therein to the accompanying drawing.

10 This invention has relation to water closet connections of that class in which a thin metal ferrule is connected to the soil pipe and provided at its upper edge with a seat to receive a collar surrounding the closet outlet.

15

In water closet connections of this character it has been customary to solder the lower edge of the ferrule directly to the soil pipe or to a metallic adjusting nipple 20 which is screwed into the soil pipe, but it has been found that in certain parts of the country, due probably to certain chemicals in the water a chemical or electrolytic action takes place that in time affects and 25 eventually completely destroys the solder joint.

The object of my present invention is to provide, in water closet connections of this character, a joining or connecting means 30 between the ferrule and the adjusting nipple that will not be deleteriously affected by chemical or electrolytic action and in carrying my invention into effect I provide the adjusting nipple of the connection with 35 an inwardly and downwardly turned ledge or flange and bring the thin metal of the ferrule down inside the downwardly projecting edge of this flange and spin it under and around the flange, so as to produce a 40 firm metal to metal and water tight joining of these parts.

As an added provision against any possible leak of water past the joint between the nipple and the ferrule, the edge of the 45 downwardly projecting portion of the flange of the nipple may be formed with a groove and this groove filled with solder before spinning the end of the ferrule around the flange and the solder fused to the nipple 50 and the ferrule after the spinning has been completed, thus producing a "blind" solder joint of the contacting parts of the nipple and ferrule.

In the accompanying drawing in which

I have illustrated my invention and in 55 which;

Fig. 1, is a vertical sectional view of my improved water closet connection.

Fig. 2, is a vertical sectional view on an enlarged scale of a modified form of the 60 connection shown in Fig. 1, this view being fragmentary and showing the connection at one side only of the closet outlet.

The water closet outlet is designated 1 and terminates in the flange or projection 2 65 which carries a collar 4 that is tapered slightly towards its lower end so as to rest in a correspondingly tapered seat formed in the metal ferrule 5.

The ferrule 5, below the tapered seat 70 bulges outwardly and then extends inwardly at an angle so as to form a somewhat funnel shaped structure, and then extends downwardly so as to enter and fit within the adjusting nipple 6, that screws into the upper 75 end of a soil pipe 7, that is formed with a laterally extending flange 8, which is connected to the closet base 9, by bolts 10.

The nipple 6, is formed with an inwardly extending flange 11, the inner and lower 80 edge of this flange extending downwardly to form a rounded shoulder 12, that is closely embraced by the lower edge portion of the ferrule 5, which is spun around the rounded shoulder 12, after the ferrule has 85 been inserted in the nipple, the portion of the ferrule which extends inwardly at an angle resting upon the inner upper edge of the flange 11, and this construction and arrangement of parts serving to hold the 90 nipple and the ferrule in strong and water tight connection under all conditions of service.

While the seal afforded by spinning the edge of the ferrule around the flange of the 95 nipple in the manner above described and as illustrated in Fig. 1, of the drawing will be found to be sufficiently tight for all practical purposes, I have made provision for an absolute hermetic seal between the ferrule and nipple, as shown in the modification Fig. 2, and wherein, in addition to having the lower edge of the ferrule spun around the flange 11 as in Fig. 1, a groove 13, is formed in the rounded shoulder 12, 100 and this groove is filled with solder before the edge of the ferrule is spun around the same and the solder, designated 14, is fused 105

to the nipple and the ferrule, thus forming a "blind" solder joint that will constitute a perfect hermetic seal and in which the solder is so covered by the edge of the ferrule as to be protected against chemical or electrolytic action to any appreciable extent.

I claim:

1. A water closet connection comprising a metallic ferrule adapted to receive the outlet projection of a closet bowl, a nipple adapted to be connected to a drain pipe, and having an inwardly projecting flange with a downwardly projecting shoulder, the said ferrule extending into said nipple and the lower end of the ferrule being spun around said shoulder.
2. A water closet connection comprising

a metallic ferrule adapted to receive the outlet projection of a closet bowl, a nipple adapted to be connected to a drain pipe and 20 having an inwardly projecting flange formed with a downwardly projecting shoulder provided with a groove, said groove being filled with solder and the lower edge of the ferrule being spun around 25 said shoulder and the solder being fused to the ferrule and nipple.

In testimony whereof I have affixed my signature in presence of two witnesses.

JOSEPH J. COSGROVE.

Witnesses:

H. Y. BLAKISTON,
AGNES M. NICKING.
